BAG MACHINE

Aubrey Koppel, Montreal, Quebec, Canada

Application January 18, 1939, Serial No. 251,654

22 Claims.

(Cl. 93—8)

The present invention relates to improvements in bag machines and more particularly to machines for turning and inserting liners into bags.

An object of the invention is the provision of a bag machine of generally improved design.

Another object of the invention is the provision of a bag machine which will completely turn the bag.

A further object of the invention is the provision of a bag machine of the aforesaid character which is capable of inserting a liner in a bag during the turning operation.

Still another object of the invention is the provision of a bag machine of the above character which is adjustable for handling bags of varying dimensions.

Still another object of the invention is the provision of a bag machine of the aforesaid character which is rapid, efficient and reliable in operation.

Still another object of the invention is the provision of a bag machine of the above character which is compact in construction.

Other objects and advantages of the invention will become apparent as the description progresses.

In the accompanying drawings forming a part of this specification and in which like reference characters are employed to designate corresponding parts throughout the same:

Figure 1 is an elevation of one side of the machine,

Figure 2 is a top plan view of the machine,

Figure 3 is an elevation of the opposite side of the machine,

Figure 4 is a vertical section through the machine,

Figure 5 is a similar view showing the mechanism in a different position,

Figure 6 is a similar view showing the mechanism in another position,

Figure 7 is a similar view with the mechanism in another position,

Figure 8 is a similar view with the mechanism in still another position,

Figure 9 is an enlarged end view of the bag feeding mechanism,

Figure 10 is an enlarged section taken on the line 10—10 of Figure 9,

Figure 11 is a section taken on the line 11—11 of Figure 10,

Figure 12 is a section taken on the line 12—12 of Figure 7,

Figure 13 is a similar view with the mechanism in a different position,

Figure 14 is an enlarged section taken on the line 14—14 of Figure 12,

Figure 15 is an enlarged fragmentary section taken substantially on the line 15—15 of Figure 1,

Figure 16 is a detailed elevation viewed from line 16—16 of Figure 1,

Figure 17 is a section taken on the line 17—17 of Figure 16,

Figure 18 is an enlarged transverse section taken substantially on the line 18—18 of Figure 3,

Figure 19 is a vertical section taken through the lower part of the machine,

Figure 20 is an enlarged detail view of part of the mechanism shown in Figure 19,

Figure 21 is a similar view with the mechanism in a different position,

Figure 22 is a fragmentary section taken on the line 22—22 of Figure 18,

Figure 23 is a section taken substantially on the line 23—23 of Figure 15,

Figure 24 is a section taken on the line 24—24 of Figure 23,

Figure 25 is a fragmentary top plan view of the machine,

Figure 26 is a fragmentary side elevational view of the same with parts removed,

Figure 27 is a similar view with the mechanism in a different position,

Figure 28 is a similar view with the mechanism in another position,

Figure 29 is an end elevational view of part of the machine, and

Figure 30 is an enlarged detail elevation of part of the mechanism.

Referring to the drawings, wherein for the purpose of illustration is shown a preferred embodiment of the invention, M generally designates the main frame of the machine, consisting essentially of a pair of vertical side sections 35, having journalled on the upper part a transversely extending shaft 36. On each projecting end of the shaft 36 is secured a spur gear 37 disposed to mesh with a smaller gear 38 secured on a stub shaft 39 and on which is also secured a sprocket wheel 40. Each gear 38 is arranged to mesh with a pinion 41 secured on another stub shaft 42 beside a pulley 43 also secured on the shaft and having a drive belt 44 trained thereover.

On the shaft 36 are secured a pair of complementary sleeves 46 each formed with a socket 47 pivotally supporting therein an arm 48 extending radially of the shaft. At the outer end of each 55

of these arms is formed an arcuate member 49 consisting of a rod curved longitudinally on a radius about the shaft and curved arcuately in cross section to provide a channel 49' having 5 rollers 50 at the ends thereof. The complementary pair of members 49 are yieldingly held in laterally spread apart positions by means of mechanism embodying a cylinder 51 formed transversely at one side of the socket 47 10 having a plunger 52 slidable therein. This plunger carries a pin 53 projecting through a slot in the cylinder wall and confined between two spaced lugs 54 extending radially from a collar 55 fixed on the arm 48. A compression coil spring 15 56 mounted in one end of the cylinder tends to thrust the plunger toward the opposite end of the cylinder and thereby maintain the arms in such position that the main body portions of the rods 49 assume relatively diverging positions, that 20 is, with the outer end portions arranged in their extreme transversely separated or spread apart positions. A pin 57 secured to the inner end of each arm 48 and projecting through a slot in the socket 47 is held against the outer end of a 25 slide rod 58 mounted in a bearing sleeve 59 and disposed so that its inner end is held in contact with a circular cam 60 formed with a recess 61. When the slide member 58 is in the recess 61 it allows the spring 56 to turn the arm 48 so that 30 the free end of each rod 49 is moved inwardly of the frame whereby these rods are caused to assume contracted or relatively adjacent positions. At all other times the slide members act against these springs to dispose the rods with the outer 35 end portions in spread apart positions.

In socket 63 extending radially from each sleeve 46 is secured a spindle 64 having a sleeve 65 rotatably fitted on its extension. At the side of the sleeve 65 is connected a curved angle bar 66 having a laterally projecting flange 67 shaped to provide a cam. A T-bar 68, fastened to each angle bar, extends in a position approximately radial to the shaft 36 and carries on its outer end a guide element 69 having a longitudinal groove at 45 its inner side, the said guides being arranged to assume positions in advance of and laterally of the free ends of the members 49. These grooved guides are curved on a radius corresponding to that of the rod members. The sleeve 65 has 50 formed thereon a transversely arranged cylinder 70 in which is mounted a slidable plunger 71 yieldingly pressed in one direction by a coil spring 72. A pin, projecting from the plunger, extends to a position between a pair of lugs 73 on the 55 fixed socket 63 so that the guide elements 69 are yieldingly urged to assume transversely spread apart positions, as shown at Figure 2.

The main shaft 36 also carries thereon an oscillatory U-shaped frame F having radial side arms 60 75 and a cross bar 76 arranged transversely thereof. At spaced positions on the cross bar are mounted a pair of blocks 77 each having a spring 78 fitted in a bore therein disposed to engage a pin 79 extending through a slot in the block 77 65 and attached to an eye-fitting 80. This eye is pivotally supported on a pivot bolt 81 and carries in its aperture the inner end portion of a rod member 82, having a diminishing taper toward its free end which terminates in a blade-shaped 70 end formation 83. The action of the spring 78 against the pin, which is arranged off centre on the eye fitting, tends to turn the eye so that the complementary pair of rods 82 will be disposed with their free ends in spread apart positions. 75 A collar 84 secured on the inner end projection

of each of the rods 82 carries an adjustable stop piece 85 arranged to contact with the cross bar 76 for regulating the diverging arrangement of the rods 82, as shown to advantage at Figures 15, 16 and 17. On the outer end of each pivot 5 bolt 64 is secured an arm 86 carrying a roller 87 on its free end portion, for a purpose which will be later described. At the inner side of each of the frame arms 75 is mounted a roller 88 arranged in position to contact with the flanges 67 10 for moving guide members 69 to inward positions at predetermined periods during the operative cycle, as will be described hereinafter. Likewise, to the inner sides of the frame arms 75 are secured the circular cam elements 60. 15

To an upstanding bracket 90 on the main frame M are secured a pair of elongated cam elements 91 shaped and mounted to engage the rollers 87 for swinging the members 82 to inward contracted positions when the frame F is elevated. 20

Another auxiliary U-shaped frame D is adapted to oscillate about the main shaft and embodies radial side arms 93 connecting at the outer ends with a cross bar 94, formed with an offset 95 intermediate its ends. The inner portions of the 25 arms 93 are fitted to slide longitudinally in a pair of slotted holder sections 96 rotatably mounted on the shaft 36 and carrying a pair of fixed laterally projecting pins 97 and 98. In an inclined 30 guide channel 99, secured to each side of the main frame, is slidably mounted a block 100 carrying a laterally projecting pin 101 and a vertically disposed arcuate arm 102 disposed to bear against the pin 97. On the inner face of each 35 of the gears 37 are secured a pair of complementary cam sections 103 and 104 shaped to provide a cam way 105 therebetween, adapted to intermittently engage the pin 101 to slide the block 100 and the arm 102 to inward positions. To an extension 106 of each holder section 96 is 40 attached one end of an adjustable connecting rod 107, the opposite end of the rod being connected by a pivot 108 to the outer end of an arm 109 forming part of the checking or damping device 110. To the pivot pin 108 is also connected the outer end of a tension spring 111 attached to a bracket 112 on the frame and tending to normally swing the frame D to an upward position. When the pin 97 is moved to a retracted 45 position, it contacts with the edge of a cam 113 50 fixed on the main frame M shaped to effect a predetermined radial movement of the frame D.

To the offset portion 95 of the frame D are hingedly connected a pair of spaced depending holder ears 115 urged to diverging positions by 55 springs 116. At the outer edge of each of the ears is mounted a fastening spring 117 bearing against the same and adapted to releasably secure a bag liner thereon. As the frame D is swung to its downward position, each pin 98 thereon 60 slides over a pivoted arcuate guide cam 118 yieldingly held in a predetermined position by a coil spring and over the outer vertical edge of a block 119 mounted in fixed position on each side of the main frame and thereafter automatically trips a 65 pivoted catch element 120 which is provided with a notch 121. A tension spring 122 functions to yieldingly hold the catch in upstanding position so that the notch therein will engage the pin 98 to lock the frame D in position. When the previously described mechanism functions to slide the frame D radially inward, each of the pins 98 disengages the notch of the catch and slides horizontally against the bottom edge of the block 119 70 so as to restrain upward swinging movement of 75

the frame D until the holding elements 115 have moved to predetermined radial positions.

At the front of the frame is provided mechanism for initially positioning and holding the bag and constitutes a fixed shaft section 124 secured rigidly in one side of the frame and extending transversely, as shown to advantage at Figures 7 to 9 inclusive. The inner end of this shaft section terminates adjacent an aligned complementary section 125 rotatably journaled in the opposite side of the frame and having secured thereon a slotted genera wheel 126. The slots of the wheel 126 are designed to engage two closely disposed rollers or pins 127 on the margin of a co-acting wheel 128, the raised boss on the latter wheel being formed with a pair of corresponding clearance recesses so that the wheel 128 will drive the adjacent wheel 126 periodically through a half-turn movement. On the rotary shaft section 125 is fastened a transversely arranged cross bar 129 engaging, in sockets at the ends, a pair of rods 130 arranged parallel with the shaft sections and connecting with the ends of a pair of complementary cross bars 131 rotatably mounted in spaced relation on the fixed section 124. To each of the bars 131 is fastened a cross arm 132, having fixed right angularly projecting jaws 133 on its ends, and carrying a pair of sleeves 134 slidably mounted thereon. These sleeves are yieldably urged to retracted inward positions on the arm by tension springs 135 and each has a laterally projecting jaw 136 formed thereon adapted to assume co-acting relation with the adjacent jaw 133 fixed on the arm. A leaf-spring 137, secured on each sleeve, is arranged to press against the inner edge of each jaw 136 to releasably grip a bag therebetween. Upon rotation of the arm actuating mechanism, one of the jaws 136 on each arm is moved to an extended position, closed against the complementary fixed jaw, while the opposite movable jaw is retracted by contact with the edge of an elongated cam 138 secured on the fixed shaft section 124, as shown to advantage at Figure 10.

The wheel 128 is fixed on a stub shaft 140 journaled on the frame which also carries a sprocket wheel 141. This shaft is driven by an endless chain 142 trained over the sprocket 141 and the sprocket 40 on the shaft 39.

The oscillatory movement of the frame F is effected, in the present example of the machine construction, by a pair of slotted levers 144 provided at each side of the main frame. Each of these levers is disposed to swing about a stub shaft 145 projecting laterally of the frame and carries in the slot thereof a longitudinally slideable block 146 which provides a bearing for a pin 147 attached to the gear 37. To the outer end of each lever 144 is pivotally connected a link bar 148 having its opposite end pivotally connected to the side of the frame F.

On each side section of the main frame, at the bottom thereof, is provided a horizontally extending endless chain 150 trained over sprocket wheels 151, said chain having connection with a crank bar 152 rotatably connected with a plate 153. This plate is mounted to slide along a pair of parallel guide rods 154. Secured to and extending between the complementary plates 154 are a pair of transversely extending rods 155 and 156, the latter having secured on its intermediate portion a pair of angular jaw elements 157 formed so that the free ends are operable to assume co-operative gripping relationship with the collars 158 secured on the rod 155. At the ends

of the rod 156 are secured a pair of levers 159, each having a relatively short extension 160 shaped at the end to form two angularly arranged bearing edges. The oppositely extending portions of each of these levers is adapted to move in a path wherein it will come in contact with the trip rod elements 161 mounted adjacent the ends of the frame. On each end of the rod 155 is secured an arm 162 depressed by a spring 163 to engage the respective angular bearing edges of the lever extension 160. This mechanism, which forms the bag removing means, may be driven by chain and sprocket connections with the sprocket 40, as shown, or by other suitable means.

The various parts of the machine are preferably counterbalanced, as illustrated, or in any preferred manner.

The operation of the machine is as follows:

A bag B, such as the jute bag commonly used for packing sugar, in the inside-out arrangement 20 in which it comes from the bag manufacturing machine, is attached to the positioning mechanism by folding down the mouth or open end marginal portion and fitting the same over the jaws 133 and 136 with the gripping springs 137 25 clamped on the inner portion, as shown at Figures 5 and 6. The bag is thereafter carried on the rotary frame in an anti-clockwise half-turn movement and held in suspended position inwardly of the frame with the upwardly disposed 30 mouth held in open position, as shown at Figure 4.

The members 49, which are adapted to rotate continuously and at a uniform speed through a circular path, are arranged to enter the open 35 bag. It is to be noted that immediately prior to entry into the bag in such take-off position, these members are caused to assume a contracted arrangement with the free ends disposed inward transversely of the frame, through the medium 40 of the springs and control cam, and maintain such positions until the ends of the rods reach the bottom of the bag. At this point the springs act to yieldingly thrust the members against the sides of the bag and carry it in transversely 45 stretched formation to a turning position. While the rods 49 move into the suspended bag the guides 69 are spread apart to pass exteriorly at the sides thereof.

During such operation, the oscillatory members 50 82 move through an upward arc from the position shown at Figure 4 to that shown at Figure 6 and, during the final stages of such movement, are contracted through the medium of the engagement of the rollers 87 with the cams 91. 55 As the rods 82 swing upward, an operator hangs a bag liner L, such as the conventional cotton bag liner, on the projections or ears 115 with the mouth in upward open position. The frame D is then moved radially inward by the cam 60 mechanism and is rapidly swung upward to the position shown at Figure 6, sliding the liner over the contracted rod members 82. Thereafter, the members 82, with the liner thereon, are swung downwardly toward the approaching carrier 65 members 49 and the guide elements 69 are moved transversely inward by the action of the cams 67 against the rollers 88 to positions operable to guide the members 82 inwardly of and parallel to the members 49. In consequence of the 70 continuing movement of the members 49 and 82, in opposite directions, the latter engage the closed bottom end of the bag body B and force it between the carrier rods while stripping it from the latter and turning the bag, that is, reversing its 75

arrangement by pushing the bag through its mouth and simultaneously inserting the liner L thereinto, as shown to advantage at Figures 7, 12 and 13. As a result of this operation, the lined bag is transferred onto the reversing members 82 with the margin of the liner projecting from the body, as shown at Figure 13, due to the fact that the holding ears maintain their grip thereon during their turning operation. During this bag reversing operation, the rods 82 are urged to open spread apart positions due to release of the rollers 87 and the action of the springs 78.

After completion of the turning the reversing members advance the bag to the removal position shown at Figure 8, at which time the bottom projections of the levers 159 are brought into contact with the rear trip rods 161, swinging the jaws to tightly grip the closed bottom end of the lined bag between the ends of the jaws and the collars 158. The jaws are locked in gripping position by the depression of the arms 162 through the medium of the springs attached thereto to engage one angular edge face of each lever extension 160, as clearly illustrated at Figure 21. Thereafter, the carrying plates 153 are slid toward the front of the frame, stripping the bag from the upwardly swinging rods 82 and depositing the bag in stacking position, preferably on a receiving truck, as illustrated at Figure 19. When the removing carrier mechanism reaches the forward end of its movement, the jaws 157 are automatically released through the engagement of the levers 159 with the forward trip rods 161 which turn the rod 156 to disengage the jaws. The jaws are held in such open or non-gripping positions by the pressure of the spring actuated arm 162 on the other angular edge face of the lever extensions 160, as shown at Figure 20, until the carriage reaches a position adjacent its extreme rearward bag engaging position. This operative cycle is continued without interrupting the movement of the machine.

Thus, the machine is adapted for turning and lining the bags in rapid succession and in a most efficient manner as the structure is such as to turn the bag with complete corner projection and with extension of the marginal liner mouth to enable convenient and efficient filling.

It is to be understood that the form of my invention herein shown and described is to be taken as a preferred example of the same, and that various changes as to the shape, size and arrangement of parts may be resorted to without departing from the spirit of the invention or the scope of the subjoined claims.

Having thus described my invention, I claim:

1. In a machine of the character described, means operable to carry a bag in an arcuate path, and means movable parallel with and in an opposite direction to said carrier means operable to engage the bag on the latter to turn and pick up the bag, and means for removing the bag from the pick-up means.

2. In a machine of the character described, means operable to carry a bag in an arcuate path, means movable parallel with and in an opposite direction to said carrier means operable to engage the bag on the latter to turn and pick up the bag, and means for removing the bag from the pick-up means.

3. In a bag machine, rotatable means adapted to enter and carry a bag through a portion of its movement, oscillatory means movable parallel with and in an opposite direction to said carrier means operable to engage the bag at a predeter-

mined position on the latter to turn and pick-up the bag, and means operable to engage the bag to remove it from the pick-up means and carry it to a stacking position.

4. In a bag machine, a pair of members rotatable in a circular path adapted to enter and carry a bag from a take-off position, and a pair of oscillatory members movable parallel with and in a direction opposite to the carrier members adapted to engage the bag on the latter to turn and pick-up the bag.

5. In a bag machine, a pair of members rotatable in a circular path adapted to enter and carry a bag from a take-off position, a pair of oscillatory members movable parallel with and in a direction opposite to the carrier members adapted to engage the bag on the latter to turn and pick-up the bag, and means adapted to engage the bag on the pick-up members to remove the same and carry it to a stacking position.

6. In a bag machine, means for positioning and holding a bag in open take-off position, rotary means operable to enter the bag and carry it from the take-off position, oscillatory means movable parallel with and in a direction opposite to the carrier means adapted to engage the bag on the latter to turn and pick-up the bag, and means for removing the bag from the oscillatory means.

7. In a bag machine, means engageable with a bag adapted to dispose the same in an open take-off position, a pair of members rotatable in a circular path adapted to enter the bag and carry it from the take-off position, a pair of oscillatory members movable in positions parallel with and in an opposite direction to said carrier members adapted to engage the bag on the latter to turn and pick it up, and means for removing the bag and depositing the same in a stacking position.

8. In a bag machine, intermittently operable mechanism adapted to engage a bag and hold the same in open arrangement in a take-off position, a pair of rotary members operable to enter the bag and carry the same in transversely stretched arrangement from the take-off position, a pair of oscillatory members movable parallel with and in a direction opposite to the carrier members adapted to engage the bag on the latter to turn and pick-up the bag, and means for positioning a liner on the oscillatory members prior to the bag turning movement thereof.

9. In a bag machine, the combination with means for turning a bag, of means for positioning a bag liner on the turning means whereby to cause said liner to be inserted into the bag body as the latter is turned.

10. In a bag machine, the combination of means for carrying a bag to a turning position, reversing means co-operable with said carrier means to turn the bag, and means for positioning and holding a bag liner on said reversing means whereby the liner will be inserted into the bag during the turning operation.

11. In a bag machine, the combination of means operable to enter a bag and carry the same from a take-off holding position, complementary reversing means co-operable with the said carrier means to effect turning of the bag, and means operable to position and hold a liner on the reversing means whereby the liner is inserted into the bag during the turning operation and a marginal portion of the open end of the liner will project beyond the mouth of the bag.

12. In a bag machine, rotary means adapted to enter and carry a bag from a take-off position,

5 oscillatory means movable in co-operative relation and in opposite direction to said carrier means to turn and pick-up the bag, and means operable to position and hold a liner on the oscillatory means whereby the liner will be positioned within the bag when the bag is turned.

10 13. In a bag machine, a frame, a rotary shaft journalled on the frame, a pair of arms secured to and extending radially from the shaft, a rod on the outer end of each arm curved on a radius referred to the shaft, means operable to yieldingly maintain the rods in open spread apart relation, and means operable to intermittently move the rods to adjacent contracted positions.

15 14. In a bag machine, a frame, a shaft journalled on the frame, an auxiliary frame mounted to oscillate about the shaft, a pair of rods curved on a radius referred to the shaft attached to the outer part of the said auxiliary frame, means for 20 yieldingly maintaining the said rods in open spread apart relation, and means operable to periodically dispose the said rods in contracted relation.

25 15. In a bag machine, a main frame, a shaft journalled transversely on the frame, an auxiliary frame mounted to oscillate about the said shaft, a pair of rods curved about the axis of the shaft attached to the said auxiliary frame, a second auxiliary frame mounted to oscillate about 30 the shaft and adjustable radially thereof, liner holding elements attached to the latter frame, means operable to periodically swing the liner holding frame, and means for releasably locking the said liner holding frame in liner receiving 35 position.

16. In a bag machine, means for carrying a bag arcuately from a take-off position, a pair of oscillatory members co-operable with the said carrier means to turn and pick-up the bag, and 40 mechanism adapted to engage a liner and slide the same over the oscillatory members whereby the liner will be inserted into the bag during the turning operation.

17. In a bag machine, means for carrying a

bag arcuately from a take-off position, a pair of oscillatory members co-operable with the said carrier means to turn and pick-up the bag, an oscillatory frame having means for holding a liner in open arrangement, mechanism for adjusting the holder means to position the liner in predetermined relation with the said members, means operable to periodically swing the said frame so as to slide the liner over the said members, and mechanism for releasably holding the frame in 10 liner receiving position.

18. In a bag machine, means for carrying a bag from a take-off to a turning position, oscillatory means co-operable with the carrier means to turn and receive the bag thereon, and reciprocating mechanism operable to grip an end portion of the bag on the oscillatory means whereby to strip the bag therefrom and carry the same to a stacking position.

19. In a bag machine, means for holding a bag 20 in open position, rotary means operable to enter and carry the bag from said holding means, and means movable parallel with the said rotary carrier means adapted to engage and take up the bag.

20. In a bag machine, oscillatory means adapted to receive a bag thereon after said bag is turned, and means for positioning a liner on said oscillatory means prior to its engagement with the bag.

21. In a bag machine, an oscillatory member, a pair of complementary bag engaging elements mounted on the said member, means for yieldingly urging the said elements to diverging positions, and means for maintaining the said elements in contracted positions when the oscillatory member is in a predetermined part of its travel.

22. In a bag machine, oscillatory means for turning and picking up a bag, and means for positioning and holding a liner on said oscillatory means.

AUBREY KOPPEL.
